NEUTRODYNING FOR SHORT WAVES

Georges Ahier and Emile Touraton, Paris, France, assignors to International Standard Electric Corp., New York, N. Y., a corporation of Delaware

Application March 20, 1947, Serial No. 735,908
In France June 18, 1945

Section 1, Public Law 690, August 8, 1946
Patent expires June 18, 1965

7 Claims. (Cl. 250—17)

1

This invention relates to a spark gap type short wave generator, and more particularly to a radio transmitter utilizing a series resonant circuit in the primary coupled to a parallel resonant circuit in the secondary to substantially prevent a secondary reaction on the spark gap after the initial primary discharge across the spark gap has been dissipated.

Due to a neutrodyning action created by a capacitive coupling between the primary and secondary circuits of the generator, the re-ignition of a spark from the secondary circuit back to the primary circuit is retarded.

An important object of the invention is to prevent, in a spark transmitter, the reaction of the secondary oscillatory circuit on the primary oscillatory circuit containing the spark gap and obtain a neutrodyne action.

Another object of the invention is a provision for installing coupling capacitors in such a way as to obtain an electrostatic coupling that is reversed with respect to the electromagnetic coupling of the inductors in the resonant circuits at wavelengths shorter than about ten meters.

Another object is to provide a radio transmitter circuit employing a primary series resonant circuit coupled to a secondary parallel resonant circuit to restrict or substantially prevent secondary reaction on the spark gap to obtain an output having a substantially linear wave shape at wavelengths shorter than about ten meters.

A further object of the invention is to provide a spark gap generator of the class set forth, which is of an extremely simplified but durable and efficient construction and arrangement of parts, and which will be comparatively inexpensive to manufacture.

Other and further objects may be and may become apparent to those skilled in the art from a perusal of this invention without departing from the spirit of the subjoined claims.

For a better understanding of the invention, reference may be had to the accompanying drawings.

In the drawings:

Fig. 1 is a schematic diagram of the circuit of a conventional spark transmitter, for comparison with the circuit of the present invention.

Fig. 2 illustrates schematically the configuration of the oscillations received at the terminals

2

of the primary and secondary circuits when spark re-ignition occurs in a circuit as shown in Fig. 1.

Fig. 3 illustrates schematically the configuration of the oscillations received at the terminals of the primary and secondary circuits without spark reignition as employed in the invention as shown in the circuit of Fig. 4.

Fig. 4 is a schematic diagram of a neutrodyne circuit of a spark transmitter embodying the invention.

Referring more particularly to the drawing, there is shown in Fig. 1 two terminals 10 and 11, the terminal 11 is connected to the ground by a lead 12 and the terminal 10 is connected to a resistor 13 by a lead 14. The other end of the resistor 13 is connected to one side of a spark gap 15 by a lead 16 and to a plate of a capacitor 17 by a lead 18. One side of a primary coil 19 of a transformer 20 is connected to the spark gap 15 by a lead 21. The other side of the primary coil 19 is connected to a plate of a capacitor 17 by a lead 22 and this lead is connected to the ground. One side of a secondary coil 23 of the transformer 20 is connected to one plate of a capacitor 24 by a lead 25 and the other side of the secondary coil 23 is connected to the other plate of capacitor 24 by a lead 26 and this lead is connected to the ground. One side of an antenna coupling coil 27 is connected to the ground by a lead 30.

In Fig. 4 there is shown a voltage source 31 connected to a resistor 32 by a lead 33 and also connected to a second resistor 34 by a lead 35. The resistor 32 is then connected to an inductor 36 by a lead 37. The resistor 34 is connected to a second inductor 38 by a lead 39. The plates of a capacitor 40 are connected to the leads 37 and 39 by leads 41 and 42 respectively. The inductor 36 is connected to one plate of a second capacitor 43 by a lead 44 and the second inductor 38 is connected to a third capacitor 45 by a lead 46. A spark gap 47 is connected with the leads 44 and 46 by leads 48 and 49 respectively. The second plate of the second capacitor 43 is connected to one side of a third inductor 50 and to one plate of a fourth capacitor 51 by a lead 52 and the second plate of the capacitor 45 is connected to the other side of the inductor 50 and the second plate of the capacitor 51 by a lead 53. The midpoint of the inductor 50 is connected to the ground. One side of an antenna coil 54 is con-

nected to the antenna 55 by a lead 56 and the other side of the antenna coil 54 is connected to the ground by a lead 57.

In operation, employing the circuit shown in Fig. 1, there is a voltage applied at the terminals 10 and 11, which, across the resistor 13, excites an oscillatory circuit comprising the capacitor 17, the spark gap 15 and the induction coil 19. This primary circuit is coupled to a secondary circuit comprising essentially the induction coil 23 and the capacitor 24, itself loosely coupled to a radiating system which is comprised of the antenna coil 27 and the antenna 28. Upon application of the voltage to the primary circuit the capacitor 17 is charged and a spark is produced across the terminals of the spark gap 15 which in turn creates oscillations of a frequency determined by the value of the capacitor 17 and the inductor 19. The secondary circuit is tuned to resonate at this frequency and there is induced in this circuit oscillations of like frequency and amplitude of those created in the primary circuit.

Figure 2 illustrates schematically the phenomena, as observed in short waves, that then occur at A in the primary circuit and at B in the secondary circuit. A beat system sets up between the primary and secondary circuits. At the moment C when the energy becomes zero in the primary circuit, it is on the contrary maximum in the secondary circuit, as shown at C'. Due to the coupling that exists between the resonant circuits, the secondary circuit then reacts on the primary circuit and re-ignites the spark which had become extinguished shortly before reaching point C, which corresponds to the time when the capacitor 17 has completely released its charge and the cycle begins anew. The phenomenon accordingly continues until renewed at point D. Under these conditions, the system does not operate as "single wave."

The Wien method makes it possible, in the known manner, to avoid this re-ignition and to obtain oscillations like those whose curves are shown in Fig. 3 and are essentially linear in wave shape. This method, however, is only applicable to spark gap generators operating on sufficiently long waves. The difficulties of de-energization occur again when dealing with waves whose length is less than about 10 meters.

The present invention aims precisely at providing a process that will prevent the re-ignition as illustrated in Fig. 2 when use is made of a spark station operating on a wavelength of less than about 10 meters.

Fig. 4 illustrates a spark station which is fed across the resistors 32 and 34 by a voltage source 31 whose mid-point is grounded. The ends of the induction coils 36 and 38 that belong to the primary circuit are connected to the ends of the induction coil 50 of the secondary circuit by the two capacitors 43 and 45. An electromagnetic coupling is set up respectively between the induction coils 36 and 38 and the halves of the induction coil 50. The mid-point of the coil 50 is placed at ground potential. The condensers 43 and 45, by means of which the capacitive coupling of the two circuits is effected, are arranged with respect to the windings of the induction coils so that the electrostatic coupling of the circuits is in reverse direction to their electromagnetic coupling. Since the voltage induced by magnetic coupling upon de-energization of the spark gap is compensated by the voltage proceeding from the capacitive coupling, re-ignition is made impossible. Therefore, with wavelengths shorter than about

10 meters, there is obtained the configuration of the representative values as those shown in Fig. 3.

The values shown in Fig. 2 are representative of the action in the circuit of Fig. 1. In the primary circuit, when the voltage is at zero at point C the voltage is at a maximum in the secondary circuit as shown at point C'. Due to the collapse of the secondary field a back electromotive force is exerted on the primary circuit which causes a second or induced spark across the gap 15, thereby creating a non-linear sinusoidal wave in the antenna circuit.

The values shown in Fig. 3 are representative of the action in a neutrodyne spark gap circuit, as shown in Fig. 4, whereby the voltage induced into the secondary circuit produces a linear sinusoidal wave in the antenna circuit but back-electromotive force is cancelled due to the interaction of the electrostatic and electromagnetic fields neutralizing each other.

From the foregoing it will be seen that a series resonant primary circuit consisting of the inductances 36, 38, and the capacitor 40, are connected to the spark gap 41. A parallel resonant secondary circuit consisting of the inductance 50 and the capacitor 51 has the input connected electrostatically by means of the condensers 43 and 45 to the output of the primary. Due to the prevention of the re-ignition of the spark gap by secondary reaction, the resultant wave form is substantially linear. The inductances 36 and 38 in the primary circuit are inductively or electromagnetically coupled to the inductance 50 in the secondary. The secondary, through the condensers 43 and 45, is electrostatically coupled to the primary, thereby producing a phase difference of 180° between the primary and the secondary. The inter-action between the primary and the secondary, in the present arrangement in the circuit of the invention results in a neutrodyne action.

While specific details of the system have been herein shown and described, the invention is not confined thereto as changes and alterations may be and may become apparent to those skilled in the art without departing from the spirit thereof as defined by the appended claims.

What is claimed as new and desired to be secured by Letters Patent of the United States, is:

50 1. A radio transmitter of the class described employing a spark gap, a series resonant primary circuit connected to said spark gap, a parallel resonant secondary circuit, and electrostatic coupling means for coupling said primary to said secondary.

55 2. A radio transmitter of the class described employing a primary circuit comprising a pair of inductances and a condenser serially connected to a spark gap, a secondary circuit consisting of an inductance connected in parallel with a condenser, and electrostatic means for coupling said secondary to said primary to obtain a transmitter output having a substantially linear wave shape in wavelengths shorter than about ten meters.

60 3. A radio transmitter of the class described employing a primary circuit comprising a pair of inductances and a condenser serially connected to a spark gap, a parallel resonant secondary circuit, and electrostatic means for coupling said secondary to said primary to obtain a transmitter output having a substantially linear wave shape.

65 4. A radio transmitter of the class described employing a series resonant primary circuit, a parallel resonant secondary circuit consisting of

an inductance connected in parallel with a condenser, and electrostatic means for coupling said secondary to said primary to obtain a transmitter output having a substantially linear wave shape in wavelengths shorter than ten meters.

5. A spark gap type short wave generator comprising a series resonant circuit in the primary circuit, a parallel resonant circuit in the secondary circuit, and a capacitative coupling between said primary and the secondary circuits of the generator to restrict passage of energy from the secondary circuit to the primary circuit tending to effect re-ignition of a spark, said coupling producing a neutrodyning action.

6. A short wave generator of the class described employing a primary circuit having a spark gap connected across the output thereof, a secondary circuit having its input connected to the output of said primary circuit, certain of the elements in the primary circuit and the secondary circuit being electromagnetically coupled, and certain means for connecting the input of the secondary circuit to the primary circuit comprising electrostatic coupling means to produce a phase difference of 180° between said primary and said secondary to the end that said phase difference prevents secondary discharges across the spark gap, thereby resulting in a substantially linear output of the wave train.

7. A short wave generator of the class described employing a primary circuit having a spark gap connected across the output thereof, and a secondary circuit having its input connected to the output of said primary circuit, certain of the elements in the primary circuit and the secondary circuit being inductively coupled, and certain means for connecting the input of the secondary circuit to the primary circuit comprising capacitive coupling means to produce a phase difference between said primary and said secondary to the end that said phase difference substantially restricts secondary discharges across the spark gap, thereby resulting in a substantially linear output of the wave train.
